(57) **CLAIM**

I claim, the ornamental design for a chassis for a tracked mobility device, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a perspective view of the chassis for a tracked mobility device of the present invention.

FIG. 2 is a front elevational view of the chassis for a tracked mobility device of FIG. 1.

FIG. 3 is a first side elevational view of the chassis for a tracked mobility device of FIG. 1.

FIG. 4 is another side elevation view of the chassis for a tracked mobility device of FIG. 1.

FIG. 5 is a rear elevational view of the chassis for a tracked mobility device of FIG. 1.

FIG. 6 is a top plan view of the chassis for a tracked mobility device of FIG. 1.

FIG. 7 is a bottom plan view of the chassis for a tracked mobility device of FIG. 1.

FIG. 8 is another perspective view of the chassis for a tracked mobility device of FIG. 1.

FIG. 9 is another perspective view of the chassis for a tracked mobility device of FIG. 1.

FIG. 10 is another perspective view of the chassis for a tracked mobility device of FIG. 1.

FIG. 11 is another perspective view of the chassis for a tracked mobility device of FIG. 1.

FIG. 12 is another perspective view of the chassis for a tracked mobility device of FIG. 1.

FIG. 13 is another perspective view of the chassis for a tracked mobility device of FIG. 1.

FIG. 14 is another perspective view of the chassis for a tracked mobility device of FIG. 1.

FIG. 15 is another perspective view of the chassis for a tracked mobility device of FIG. 1.

FIG. 16 is another perspective view of the chassis for a tracked mobility device of FIG. 1.

FIG. 17 is another perspective view of the chassis for a tracked mobility device of FIG. 1.

FIG. 18 is another perspective view of the chassis for a tracked mobility device of FIG. 1.

FIG. 19 is another perspective view of the chassis for a tracked mobility device of FIG. 1.

FIG. 20 is another perspective view of the chassis for a tracked mobility device of FIG. 1.

FIG. 21 is another perspective view of the chassis for a tracked mobility device of FIG. 1; and,

(Continued)

FIG. 22 is another perspective view of the chassis for a tracked mobility device of FIG. 1.
